(57) **CLAIM**

The ornamental design for a hand tool as shown and described.

DESCRIPTION

FIG. 1 is a perspective view of an embodiment of a hand tool viewed from a first end, including an exemplary tool head; FIG. 2 is a perspective view of an embodiment of the hand tool viewed from the first end, excluding the exemplary tool head removed;

FIG. 3 is a first end view of an embodiment of the hand tool, including the exemplary tool head;

FIG. 4 is a first end view of an embodiment of the hand tool, excluding the exemplary tool head;

FIG. 5 is a first side view of an embodiment of the hand tool, including the exemplary tool head;

FIG. 6 is a second side view of an embodiment of the hand tool, including the exemplary tool head;

FIG. 7 is a third side view of an embodiment of the hand tool, including the exemplary tool head;

FIG. 8 is a fourth side view of an embodiment of the hand tool, including the exemplary tool head;

FIG. 9 is a perspective view of an embodiment of the hand tool viewed from a second end, including the exemplary tool head at the first end;

FIG. 10 is a perspective view of an embodiment of the hand tool viewed from the second end, excluding an end cap, including the exemplary tool holder positioned within an internal cavity of the hand tool, and including the exemplary tool head at the first end.

FIG. 11 is a second end view of an embodiment of the hand tool, excluding the end cap, and including an exemplary tool holder positioned within the internal cavity of the hand tool;

FIG. 12 is a perspective view of an embodiment of the hand tool viewed from the second end, excluding an end cap, depicting the internal cavity of the hand tool; and,

FIG. 13 is a second end view of an embodiment of the hand tool, excluding the end cap, depicting the internal cavity of the hand tool.

The broken lines illustrate portions of the design that form no part of the claim.
